UNITED STATES PATENT OFFICE.

FREDERICK W. WAKEFIELD, OF VERMILION, OHIO, ASSIGNOR TO THE F. W. WAKEFIELD BRASS COMPANY, OF VERMILION, OHIO, A CORPORATION OF OHIO.

DESIGN FOR A COMBINED LIGHTING FIXTURE AND CLAMP THEREFOR.

Application filed October 8, 1925. Serial No. 15,058. Term of patent 14 years.

To all whom it may concern:

Be it known that I, FREDERICK W. WAKEFIELD, a citizen of the United States, and a resident of Vermilion, county of Erie, and State of Ohio, have invented a new, original, and ornamental Design for a Combined Lighting Fixture and Clamp Therefor, of which the following is a specification, reference being had to the accompanying drawing, forming part thereof.

In said annexed drawing:—

Fig. 1 is a side elevational view of the fixture, the supporting member being shown in dotted lines, and, Fig. 2 is a top plan view of the device.

I claim:—

The ornamental design for a combined lighting fixture and clamp therefor as shown.

Signed by me, this 7th day of October, 1925.

FREDERICK W. WAKEFIELD.
